FLORENCE C. BIGGERT, JR., OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

CONTINUOUS-SHEET MILL AND METHOD OF MAKING FINISHED SHEETS.

Application filed September 7, 1923. Serial No. 661,406.

The present invention relates broadly to the metal working art, and more particularly to continuous sheet mills and an improved method of making finished sheets 5 from slabs.

By the present invention, it is possible to perform a series of operations beginning with the heated slabs coming from the heating furnaces at one end of the mill and ending with the piles of finished sheets at the 10 other end of the mill. These operations are performed in a continuous manner as the material advances step by step through the mill and may include breaking the scale from the 15 slabs, rolling them into thin sheets, cutting and trimming the sheets to the required size, superposing the sheets in the desired manner to form packs, doubling the packs and charging them into a reheating furnace. The 20 reheated packs may then be rolled to further reduce the thickness of the individual sheets, mechanically operated upon by means for loosening the sheets and then passed over a hot bed to reduce the temperature thereof 25 to a working temperature. Thereafter the packs may again be mechanically operated upon to further loosen the sheets, and the individual sheets then separated and piled.

Another object of the invention is to provide 30 a mill embodying means for piling the sheets in a novel manner whereby packs of uniform thickness may be obtained.

A further object of the invention is to provide 35 a mill embodying novel means for doubling the piled sheets.

A still further object of the invention is to provide a mill embodying novel means for separating the individual sheets in the 40 packs.

Other important objects of the invention will be apparent as the description proceeds.

In the accompanying drawings, there is shown, for purposes of illustration only, one embodiment of the present invention, it being understood that the drawings do not define the limits of the invention, as changes may be made in the construction and operation therein disclosed without departing from the spirit of the invention or scope of 45 my broader claims.

In the drawings, Figure 1 is a diagrammatic plan view illustrating the layout of the one end portion of a mill constructed in accordance with my invention.

Figure 1^a is a view similar to Figure 1, 55 illustrating the other end portion of the mill layout.

Figure 2 is a vertical longitudinal sectional view through the scale breaker and roughing and finishing rolls shown in Figure 1. 60

Figure 3 is a view partly in section and partly in elevation illustrating the sheet turning and piling mechanism and the mechanism for doubling the packs.

Figures 4 and 5 are views similar to the 65 left-hand portion of Figure 3, illustrating different operative positions of the sheet turning and piling mechanism.

Figures 6, 7 and 8 are views illustrating different operative positions of the mechanism 70 for doubling the packs.

Figure 9 is a plan view of the sheet separating mechanism; and

Figure 10 is a view partly in section and partly in elevation of the structure shown in 75 Figure 9.

The general plan of a mill layout in accordance with my invention is illustrated in Figures 1 and 1^a, wherein is shown a continuous sheet mill embodying furnaces A for 80 heating the slabs, a scale breaker B, roughing and finishing rolls C, shearing mechanism D, pinch rolls E, sheet turning and pack-forming mechanism F, mechanism G for doubling the packs, charging and discharging means 85 H for a reheating furnace I, a traveling table J, rolls K, shearing mechanism L, a deep buckling leveler M, a hot bed N, a deep buckling leveler O, a transfer table P, sheet separating mechanism Q, pinch rolls R, and sheet 90 pilers S.

Referring to Figures 1 and 2, it will be seen that the scale breaker B consists of a set of leveling rolls 2 actuated by a suitable motor 3. The roughing and finishing rolls C, for 95 rolling the sheets individually, comprise edge rolls 4 and a plurality of stands of three-high rolls, eight of such stands being shown, each stand comprising two large rolls 5 between which is arranged a smaller roll 6. 100 The rolls 5 and 6 are arranged to be driven by suitable motors 7 through driving means 8. The purpose of passing the material between a large roll 5 and a smaller roll 6 is to secure as nearly as possible a line contact 105 between the material being rolled and the surfaces of the rolls, the advantages of this method of rolling being well understood in

the art. It will be noted that the arrangement of the stands of rolls is such that the material passes alternately between a lower large roll 5 and a small roll 6 and between an upper roll 5 and a small roll 6, whereby to secure greater uniformity of rolling.

The sheet turning and piling mechanism is illustrated in detail in Figures 3, 4, and 5, and comprises a table 9 for receiving the sheets from the pinch rolls E. Arranged beneath the table 9 is a rock-shaft 10, which has mounted thereon arms 11. Positioned at one side of table 9 and extending parallel thereto is a second rock-shaft 12 having mounted thereon turning arms 13 which normally occupy a horizontal position.

The operation of the turning and piling mechanism is as follows: Assuming the parts in the position illustrated in Figure 3, and a sheet *a* on the table 9, the arms 11 are rocked in a counter-clockwise direction from the position shown in Figure 3 into the position shown in Figure 4, whereby the sheet *a* is pushed off the table 9 onto the arms 13. Another sheet *b* is then fed onto the table 9 and thereafter the arms 13 are rocked into the vertical position illustrated in Figure 5, whereby the sheet *a* is inverted and deposited upon the sheet *b* to form a pair. The arms 11 and 13 are then returned into the positions in which they are shown in Figure 3, whereby the arms 11 push this pair from the table 9 onto a transfer table 14. The object of turning alternate sheets in this manner is to produce a pack of uniform thickness. In rolling the sheets, it is found that in practice the sheets are apt to be rolled slightly thinner at one edge than at the other, so that, if a plurality of sheets were piled upon one another just as they came from the last stand of rolls, this lack of uniformity in thickness of the individual sheets would be magnified in the pack and the latter would be considerably thinner at one edge than at the other. By inverting alternate sheets, each pair of superposed sheets will be of substantially uniform thickness and when a number of pairs of sheets are piled, the resulting pack will also be of substantially uniform thickness.

Any desired number of pairs of superposed sheets *a* and *b* may be piled and transferred over the transfer table 14 onto another table 15, shown in Figure 3, parallel to the table 9. The table 15 constitutes part of the mechanism for doubling the packs so formed. Preferably two pairs of superposed sheets *a* and *b* will be piled and transferred to the table 15 forming a pack having a thickness of four sheets.

The doubling mechanism comprises a fluid-pressure cylinder 16 arranged laterally of the table 15 and extending at right angles to the length thereof. Carried by the piston of the cylinder 16 is a narrow flat plate or arm 17 adapted to be projected over the middle of

the pack on the table 15, as illustrated in dotted lines in Figure 3 and in full lines in Figure 6. The free end of the plate or arm 17 is tapered and adapted to engage beneath a roller carried by a lever 18 pivoted at one side of the table 15, whereby the plate or arm 17 is forced down upon the pack into firm clamping engagement therewith. A section of the table 15 is formed by a folder 19 supported at one end upon a rock-shaft 20 extending transversely of the table adjacent the position occupied by the plate 17 when the latter is projected across the table. Normally the folder occupies the horizontal position illustrated in Figure 6. When the plate 17 has been moved across the pack into clamping engagement therewith, as illustrated in Figure 6, the folder is rocked into position illustrated in dotted lines in Figure 7 and in full lines in Figure 8. It will be noted that the folder has a portion 19' extending from the rock-shaft 20 and joining the main portion 19" at an angle. The folder carries at the angle between the portions 19' and 19" thereof a pinch roll 21 adapted for cooperation with a pinch roll 22 carried by the table 15 to iron out the fold in the doubled pack. This ironing out of the fold is accomplished by first withdrawing the plate or arm 17 after the folder is rocked into the dotted line position illustrated in Figure 7, and then drawing the pack along the table 15 to move the folded end portion thereof between the pinch rolls.

After a pack has been doubled in the manner described, it is transferred to the charging and discharging mechanism H which carries it into the reheating furnace I.

After the pack has been reheated, it is withdrawn from the reheating furnace I and transferred over the movable table J and passed through a plurality of stands of rolls K similar to the rolls C. After the pack has been passed through the rolls K, it is carried to the shearing mechanism L whereby the pack, including the folded edge thereof, is trimmed. The pack is next passed through the deep buckling lever M, consisting of a plurality of overlapping leveling rolls, whereby the sheets in the pack are loosened. The loosened pack is then transferred to the hot bed N and permitted to cool to a working temperature. At this temperature it is passed to the deep buckling leveler O which further loosens the individual sheets in the pack. The loosened pack passes to the table P from which it is transferred to any one of the sheet separating and stripping mechanisms Q.

A sheet separating and stripping mechanism Q is illustrated in detail in Figures 9 and 10. It comprises a pair of vertical standards 23 spaced a sufficient distance apart to receive a pack of sheets between them and connected by suitable brace rods 24 carried

by brackets 25 fixed to the standards, the rods 24 being positioned slightly below the path of travel of the pack between the standards in order to form a temporary support for the pack. The separating device also comprises a pair of gripping tongs 26 pivoted together at 27 and adapted to grip the leading end of the pack, as illustrated in Figures 9 and 10. The gripping tongs 26 carry a pair of flanged rollers 28 engaging tracks 29. The free end portions of the arms of the gripping tongs 26 extend at an angle to and cross each other and are engaged by a link 30 carried by a suitable casting 31 having an eye 32. Any suitable power device may be connected with the casting 31 through the eye 32 to pull the gripping tongs 26 along the tracks 29 in order to draw the pack between the standards 23 and cause rods 33, inserted between the sheets and engaging against one edge of the standards 23, to strip and separate the individual sheets in the pack. The insertion of these rods 33 is made possible due to the loosening of the sheets caused by passing the same through the deep buckling levelers. After the rods are all in position, the free ends of the sheets may be easily gripped by the tongs 26.

After the sheets have been separated, as previously described, they may be passed through the pinch rolls R and piled upon the tables S, ready for further treatment or disposal.

The operation of the mill, as a whole, may be briefly summarized as follows: The slabs to be rolled into sheets are first heated in the furnaces A and then passed individually through the scale breaker B and the rolls C. As illustrated, there are eight stands of these rolls, and if we assume a slab having an initial thickness of $2\frac{1}{2}$ ", these eight stands of rolls may reduce its thickness to .12". The sheets are trimmed by the shear mechanism D and then pass through the pinch rolls E to the sheet turning and pack forming mechanism F, by which they are turned and piled, as previously described in detail. The packs are then doubled by the doubling mechanism G and reheated in the furnace I for passage through the rolls K. These rolls reduce the thickness of the packs, so that a pack of eight sheets, for example, may be reduced to a thickness of, say, .12", whereby the individual sheets in the pack have a thickness of .015". The packs pass from the rolls K to the shearing mechanism L, by which they are suitably trimmed and then they pass through the deep buckling leveler M, over the hot bed N, through the deep buckling leveler O, to the separating devices Q and finally to the pilers S. These operations occur in proper sequence with a minimum of attention and manual labor.

An important advantage of the invention

arises from the provision of a mill whereby a series of operations may be performed in a continuous manner to produce finished sheets from slabs.

Another important advantage of the invention arises from the provision of a mill having novel pack forming means.

Still another advantage of the invention arises from the provision of a mill having novel means for doubling the packs.

A further advantage of the invention arises from the provision of a mill having novel means for separating and stripping the individual sheets in the packs.

A still further advantage of the invention arises from the provision of a mill in which all of the necessary operations to produce finished sheets from slabs may be performed step by step while the material is continuously advancing through the mill.

My application, Serial No. 146,126, filed November 4th, 1926, is a division of this application and covers the pack opening mechanism herein described.

I claim:

1. In a mill, a support arranged to receive a pack of sheets, a clamping member, means for positioning said clamping member across an intermediate portion of said pack, means cooperating with said clamping member for automatically forcing the same into clamping engagement with said pack, and roller means for doubling said pack about said clamping member, substantially as described.

2. In a mill, a support arranged to receive a pack of sheets, a clamping member, means for positioning said clamping member across an intermediate portion of said pack, means cooperating with said clamping member for automatically forcing the same into clamping engagement with said pack, and means for doubling said pack about said clamping member, said last mentioned means including means for ironing out the folded end portion of said pack, substantially as described.

3. In a mill, a support arranged to receive a pack of sheets, means cooperating with said support for clamping an intermediate portion of said pack between said means and support, pivotally mounted means for doubling said pack about said clamping means, and a pair of cooperating pinch rolls carried respectively by said doubling means and support for ironing out the folded end portion of said pack, substantially as described.

4. In a mill, a support arranged to receive a sheet to be folded, a clamping member, means positioned at one side of said support and having said member operatively secured thereto adapted to project said member across said support, means at the other side of said support adapted to be engaged by the free end of said member whereby to force the latter in clamping engagement with the

- sheet, and means providing line contact with the sheet for doubling the sheet about said member, substantially as described.
5. In a mill, sheet rolling means, pack forming and doubling means, pack heating and rolling means, means for mechanically operating upon a pack to loosen the sheets therein, and means for separating all of the sheets in said pack, substantially as described.
- 10 6. In a method of manufacturing sheets, the steps consisting in rolling a pair of sheets, inverting one of the sheets and superposing it upon the other sheet, and then rerolling the superposed sheets, substantially as described.
- 15 7. In a method of manufacturing sheets, the steps consisting in forming a pair of sheets by rolling a sheet and placing it upon turning means, rolling a second sheet and positioning it adjacent said turning means, 20 then actuating said turning means to invert the first sheet and superpose it upon the second sheet, and then re-rolling the superposed sheets, substantially as described.
8. In a method of manufacturing sheets, 25 the steps consisting in individually rolling a plurality of sheets, superposing said sheets to form a pack, doubling said pack, ironing out the folded end portion of said pack, and rolling the pack, substantially as described.
- 30 9. In a method of manufacturing sheets, the steps consisting in superposing a plurality of sheets to form a pack, placing clamping means in engagement with an intermediate portion of said pack, doubling said pack 35 about said clamping means, withdrawing said clamping means from said pack, ironing out the folded end portion of said pack, and rolling the pack, substantially as described.
- 40 10. In a method of manufacturing sheets, the steps consisting in superposing a plurality of sheets to form a pack, placing clamping means in engagement with an intermediate portion of said pack, doubling said pack 45 about said clamping means, withdrawing said clamping means from said pack, moving said pack between ironing means to iron out the folded end portion thereof, and rolling the pack substantially as described.
- 50 11. In a method of manufacturing sheets, the steps consisting in forming a pack of superposed sheets providing at least four thicknesses, reheating and rolling said pack, loosening said pack, inserting stripping means between the individual sheets in said pack, and producing relative movement between the pack and stripping means whereby to separate the sheets from each other, substantially as described.
- 55 12. In a method of manufacturing sheets, the steps consisting in rolling the sheets in succession, inverting alternate sheets and piling the sheets so as to form pairs, piling any desired number of said pairs to form a pack,
- doubling said pack, ironing out the folded end portion thereof, and rolling the pack substantially as described.
13. In a method of manufacturing sheets, the steps consisting in rolling individual sheets, superposing said sheets to form a pack, doubling said pack, reheating and rolling said pack, mechanically operating upon said pack to loosen the sheets therein, inserting stripping means between said sheets, and producing relative movement between said pack and stripping means to separate the sheets, substantially as described.
14. In a method of manufacturing sheets, the steps consisting in subjecting a pack of sheets to a series of buckling operations to 80 loosen the sheets, cooling the sheets intermediate successive buckling operations, inserting stripping means between the loosened sheets, and producing relative movement between said stripping means and pack to separate the sheets 85 in the pack, substantially as described.
15. In a method of manufacturing sheets, the steps consisting in subjecting a pack of sheets to a series of buckling operations to 90 loosen the sheets, individually inserting stripping means between the loosened sheets, producing relative movement between said stripping means and pack to separate the sheets 95 in the pack and piling the sheets, substantially as described.
16. In the method of manufacturing sheets, the steps consisting in forming a pair of sheets by rolling a sheet and placing it upon turning means, rolling a second sheet and 100 positioning it adjacent said turning means, actuating said turning means to superimpose said sheets with one of the sheets reversed edge for edge relatively to the other sheet, doubling said superimposed sheets, and then 105 re-rolling the pack thus formed substantially as described.
17. In the method of manufacturing sheets, the steps consisting in rolling a pair of sheets, superimposing one of the sheets on the other 110 with one of the sheets having its edges reversed edge for edge with respect to the other sheet, and then rolling the superimposed sheets substantially as described.
18. In a mill, sheet rolling means, means 115 for forming a pack with certain of the sheets reversed edge for edge with respect to the other sheets, means for doubling the pack, pack heating and rolling means, means mechanically operating upon a pack to loosen 120 the sheets thereon, and means for separating all of the sheets in said pack, substantially as described.
19. In the method of manufacturing sheets, the steps consisting in superposing a plurality 125 of sheets in edge for edge reversed relationship to form a pack, placing clamping means in engagement with an intermediate portion

of said pack, doubling said pack about said clamping means, withdrawing said clamping means, from said pack, and then rolling the pack substantially as described.

5 20. In a method of manufacturing sheets, the steps consisting in rolling the sheets in succession, superposing the successive sheets

in reversed relationship edge for edge to form pairs, forming any desired number of said pairs into a pack, and then rolling the pack, substantially as described.

In testimony whereof I have hereunto set my hand.

FLORENCE C. BIGGERT, JR.
